Primary Examiner — Deanna L Pratt

(74) Attorney, Agent, or Firm — Ansari Katiraei LLP;
Arman Katiraei; Sadiq Ansari(57) CLAIM

I claim the ornamental design for a three panel vanity mirror with surface lights, as shown and described.

DESCRIPTION

FIG. 1 is a perspective view of a three panel vanity mirror with surface lights, showing my new design;

FIG. 2 is a front view thereof;

FIG. 3 is a back view thereof;

FIG. 4 is a top view thereof;

FIG. 5 is a left view thereof; and,

FIG. 6 is a right view thereof.

The broken lines depict environmental subject matter that forms no part of the claimed design.
